UNITED STATES PATENT OFFICE.

FRANK JOHN EBLE, OF NEW YORK, N. Y.

SAFETY ATTACHMENT FOR RANGES.

1,265,183.

Specification of Letters Patent.

Patented May 7, 1918.

Application filed June 29, 1916. Serial No. 106,699.

To all whom it may concern:

Be it known that I, FRANK J. EBLE, a citizen of the United States, residing at New York city, in the county of New York and 5 State of New York, have invented certain new and useful Improvements in Safety Attachments for Ranges; and I do declare the following to be a full, clear, and exact description of the invention, such as will enable others skilled in the art to which it 10 app pertains to make and use the same:

This invention relates to new and useful improvements in safety attachments for gas ranges, and the primary object of the invention is to provide an attachment of this 15 character that is adapted to be secured to the valves that control the burners at the top and bottom of the oven, so that only one burner may be used at a time thereby preventing 20 any chance of an explosion in the oven.

Another object of the invention is to provide a device of this character which is inexpensive to manufacture, durable and highly efficient for the purposes for which 25 it is intended.

With these and other objects in view, my invention resides in the novel features of construction, combination and arrangement of parts to be hereinafter more particularly 30 pointed out in the specification and claim.

In the accompanying drawings:—

Figure 1 is a perspective showing my attachment applied to a gas range;

Fig. 2 is a detail perspective of the locking strip;

Fig. 3 is a detail perspective of one of the operating handles and the locking pin.

In describing my invention, I shall refer to the drawings in which similar reference 40 characters designate corresponding parts throughout the several views and in which the numeral 1 designates a conventional type of gas range to which this attachment is applied, having a vertical manifold main supply pipe 2 along one side, that has projecting therefrom a pair of branch supply pipes 3, which lead to the burners at the top and bottom of the oven. The branch supply pipes 3 are provided with valves 4, which are of 45 the conventional type used in stoves of this character.

The above recited elements are common to various types of gas ranges, employing an oven, although the arrangement and positioning may be slightly different in different stoves, the manifold and branch supply 55

pipes will be arranged in the same relation in all types.

My improved safety attachment consists of a pair of horizontally disposed parallel handles 5 which have their inner ends 6 bifurcated, and attached to the valves 4 in the branch supply pipes. A locking pin 7 is positioned through alining openings in the bifurcated portions of the handles, and also 60 an opening in the top of the valve, so that the handles will be operatively connected with the valves. This pin 7 is readily detachable, so that the handles may be attached to or removed from the valves by a very 65 quick and simple operation. The other ends of the handles 5 are received in slots in the ears 8, that are attached to the side of the gas stove shown in the accompanying drawings, and these handles are adapted to rotate 70 freely within the ears.

Projecting from the sides of the handles 5 at opposite points are laterally extending lugs 9 and 10, which are formed integral with the handles, and are positioned in alignment with each other. These projecting lugs 9 are adapted when the valves are closed to be disposed in parallel relation, but when one of the valves is open, the lugs are turned with the handle so that they will be positioned at right angles to the lugs of the adjacent handle. Slidably mounted on the side of the stove 1 between the parallel handles 5 is a strip 11, which has its upper end bent laterally outwardly as shown at 12, while its lower end is inclined downwardly and outwardly as shown at 13 with its extremity bent horizontally as shown at 14. This strip 11 is mounted on the side of the stove 1 by projecting headed studs 15 that are positioned through elongated slots 16 in the strip.

In Fig. 1 of the drawings, I have shown my safety attachment applied to a gas stove, with the lower valve that operates the bottom burner of the oven open, while the upper valve is closed and locked. By this arrangement, it will be obvious that to open the lower valve it is necessary to turn the lower handle 5 and that consequently the 100 projecting lugs 9 engage successively the inclined portion 13 and extremity 14 of the lower end of the strip 11, and force the same upwardly, until the end of the lug is positioned beneath the extremity of the strip 105 110 as clearly shown in Fig. 1 of the drawings. When in this position, the out-turned end 12

at the upper end of the strip will be stationary beneath the lug 10 on the upper handle 5, so that it will be impossible to turn this handle to open the upper valve.

5 As soon as the lower valve is cut off, the projecting lugs on the lower handle will resume their normal position parallel with the lugs on the upper handle, and the strip 11 will be free to move upon the rotation of 10 the upper handle as the projecting lugs 10 will force the strip downwardly and consequently will lock the lower valve.

This attachment affords an easy and efficient safety means, that may be readily attached to a gas range and which will prevent both burners in the oven from being operated at the same time. The danger of this is well known and explosion often results from ranges that are not provided 20 with some safety attachment to prevent the operation of both burners. This attachment may be easily applied to any type of gas range, it only being necessary to secure the ears 8 in which the handles are mounted thereto, and attach the bifurcated ends 25 of the handles to the valves. The sliding locking strip between the handles may be easily secured thereto in the manner hereinbefore described.

30 It will be noted that during the operation of the device, only the lugs 9 on the lower handle and 10 on the upper handle will be used, but the lugs on the opposite sides of these handles are placed there so 35 that in case the handles should be placed on backward, this device would operate regardless. When lugs are only used on one side of the handles, great care has to be taken to place the handles in correct position or 40 the safety device will not operate. By plac-

ing the lugs on both sides of the handles, any person not skilled in the operation of this attachment may secure the same to the stove and it will be sure to operate.

From the foregoing description, the construction and operation of my improved safety attachment for gas ranges, the manner of placing the same to use and the operation thereof will be readily understood, and it will be seen that I have provided a 50 simple and efficient device for carrying out the objects of this invention.

I claim:

In combination with a gas stove, a main supply pipe for the same, a pair of spaced 55 branch pipes connected to said main pipe, valves in said branch pipes, parallel operating handles having bifurcated ends for engagement with said valves, ears projecting outwardly from said stove and secured 60 thereto, said ears being provided with slots to receive said operating handles, integrally formed lugs projecting from both sides of said handles whereby to prevent the application of the handles in an inoperative position, said lugs disposed in parallel relation when the valves are closed, a locking strip 65 slidably mounted on studs projecting from the side of said stove, said locking strip having outturned ends adapted to engage said 70 lugs whereby to prevent the opening of both valves simultaneously.

In testimony whereof I have hereunto set my hand in the presence of two subscribing witnesses.

FRANK JOHN EBLE.

Witnesses:

PAUL W. ZOLL,

WILLIAM J. CAMPBELL.
